UNITED STATES PATENT OFFICE.

WESLEY W. HAUENSTEIN, OF CHICAGO, ILLINOIS.

CURTAIN-HANGER.

SPECIFICATION forming part of Letters Patent No. 625,503, dated May 23, 1899.

Application filed March 11, 1898. Serial No. 673,432. (No model.)

To all whom it may concern:

Be it known that I, WESLEY W. HAUENSTEIN, a citizen of the United States of America, residing in Chicago, county of Cook, and 5 State of Illinois, have invented certain new and useful Improvements in Curtain-Hangers, of which the following is a description.

Referring to the accompanying drawings, wherein like reference-letters indicate like or corresponding parts, Figure 1 is a side elevation of my improved form of hanger. Fig. 2 is a similar view showing the position of the parts as a clasp is in the act of closing. Fig. 3 is a similar view showing the clasp completely closed. Fig. 4 shows the blank of which the separable lever-seat is composed. Fig. 5 shows the lever-seat bent up in proper form and the relation of the same with the clasp. Fig. 6 shows the blank for the ring and clasp. Fig. 7 is a view of a modification in which the lever-supporting piece is shown secured in position by tangs embracing the blank, and Fig. 8 is a sectional view on line 8-8 of Fig. 7. Fig. 9 is a sectional view showing a modified form of lever.

The object of my invention is to produce a simple, effective, and economical curtain-hanger which will facilitate the easy hanging and taking down of curtains and similar articles.

To this end it consists in the novel construction and combination of parts shown and described, and particularly pointed out in the claims.

In the drawings, N is a ring adapted to be placed upon a pole in the usual manner for the support and arrangement of lace or other curtains. The ring is not closed, and being of a spring or resilient construction has a tendency to spring apart, as shown in Fig. 2. The ends of the blank are extended and bent outward, as shown, terminating at the ends in two opposing elements a a' of a clasp. On one of the elements, as a , is secured a separate U-shaped piece O, providing lever-supporting arms C C' for the lever D, which is of a form adapted by its operation to close the clasp a a' or to release the same. The simple form shown serves this purpose. In this form the lever is bent at an angle, forming a bell-crank lever, and being pivotally supported substantially on a line with the angle of the

lever to the arms C C', which extend on either side of the part a' , it will be readily seen that upon moving the free end of the lever up, as 55 shown in Fig. 3, the inner end of the lever will bear against the side of part a' , the action being to draw the two parts a a' of the clasp together and securely retain the fabric of the curtain without cutting or tearing the 60 same.

The simple manner adopted by me to pivotally support the lever is apparent from the drawings. The supports are punched out, forming holes c c' , and the lever is provided 65 with extensions d , one on each side thereof, adapted to be loosely seated therein.

It is evident from a glance at Fig. 9 that the lever D can be bent oppositely from the form shown in the other figures and made to 70 close the clasp by a downward instead of an upward movement.

To prevent displacement of the parts, I also provide the shoulders a^3 a^3 conveniently by reducing the width of the blank at n' , forming a guide for the arms C C', and also provide shoulders a^2 a^2 conveniently by reducing the width of the blank at n to form a retaining means to hold the U-shaped lever-support 75 O in proper position on the blank. 80

Figs. 7 and 8 are enlarged detail views showing the blank and lever-supporting arms C C' and one means of firmly securing the latter to the former. The V-shaped piece constituting these arms C C' is secured to the blank, 85 for example, as shown in the drawings, in which the projecting parts c^2 c^2 are clasped about the blank, preferably fitting or registering with a depressed seat to fix the location and prevent displacement. 90

I prefer to construct one of the guides, as n' , of greater width than the other in order that that member of the clasp may have suitable play in operating the lever. (See Fig. 2.) The other guideway I prefer to make of a 95 size that will permit of the lever-support O being snugly seated therein.

Having thus described my invention, what I claim as new, and desire to secure by Letters Patent, is—

1. A curtain-hanger comprising an open ring having end portions extending outwardly therefrom and forming the opposing members of a clasp or clamp, one of said end portions

having a part thereof reduced in width, a separate U-shaped piece secured to said end portion in said reduced part and providing lever-supporting arms, and an operating-lever pivoted to said supporting-arms and acting on the other clamp member to positively operate the same, substantially as described.

2. A curtain-hanger comprising an open ring having end portions extending outwardly therefrom and forming the opposing members of a clasp or clamp, one of said end portions having a part thereof reduced in width, a separate U-shaped piece secured to said end portion in said reduced part and providing lever-supporting arms, guides on said other end portion in which said lever-supporting arms are guided and an operating-lever pivoted to said supporting-arms and acting on the other clamp member to positively operate the clamp, substantially as described.

3. A curtain-hanger comprising an open ring having end portions extending outwardly therefrom and forming the opposing members of a clasp or clamp, one of said end portions

having a part reduced in width, a separate U-shaped piece providing lever-supporting arms secured to said end portions in said reduced part by means of holding-tangs on said U-shaped piece embracing said end portion, an operating-lever pivoted to said supporting-arms and acting on the other clamp member for positively operating the clamp, substantially as described.

4. A curtain-hanger, comprising an open ring having end portions extending outwardly therefrom and forming the opposing members of a clasp or clamp, one of said portions having shoulders thereon, a separate U-shaped piece secured to said end portion between said shoulders and providing lever-supporting arms, and an operating-lever pivoted to said supporting-arms and acting on the other clamp member to positively operate the same, substantially as described.

WESLEY W. HAUENSTEIN.
